UNITED STATES PATENT OFFICE.

ALMERON M. LANE, OF MERIDEN, CONNECTICUT.

CLOCK STRIKING MECHANISM.

SPECIFICATION forming part of Letters Patent No. 403,275, dated May 14, 1889.

Application filed August 13, 1888. Serial No. 282,546. (No model.)

To all whom it may concern:

Be it known that I, ALMERON M. LANE, a citizen of the United States, residing at Meriden, in the county of New Haven and State of Connecticut, have invented certain new and useful Improvements in Clocks, of which the following is a specification.

My invention relates to improvements in clocks which have striking mechanisms; and the objects of the improvement are to enable the striking mechanism to be mounted outside of the clock-case in a neat and attractive form, and also to connect the striking mechanism with the time-movement in a convenient and efficient manner, and so that they may be easily detached for repairs.

In the accompanying drawings, Figure 1 is a partial vertical section and partial elevation of my clock, the plane of section extending at right angles to the center shaft. Fig. 2 is a partial vertical section of a portion of said clock, the plane of section extending through the axis of the center shaft; and Fig. 3 is a horizontal section of the base and plan view of the striking mechanism with the top plate removed.

A designates the clock-case, containing within it a time-movement of any ordinary construction, said case being mounted upon a base, B, which contains within it a striking mechanism, C, of any ordinary construction. Upon the center shaft, 4, of the time-movement I arrange a cam, 5—in the present instance having two arms or shoulders, so as to operate the tripping-lever every half-hour, the striking mechanism being adapted to strike the half-hour as well as the hours of the day. In case a striking mechanism is employed which does not strike the half-hour, then the cam 5 would be provided with only one arm or shoulder.

Upon one of the time-movement plates I mount a tripping-lever, 6, the upper end of which extends upward, so as to be engaged by the cam, while the lower end extends downwardly to a point near the lower side of the clock-case. The striking mechanism C is mounted with its plates in a horizontal position within the base, as shown. The warning-wire 7 is of ordinary construction, and is

mounted upon the shaft 8, from which extends an arm, 9, the end of which is bent upwardly and passes through openings into the clock-case A to a point by the side of the lower end of the lever 6, as shown in Figs. 1 and 2. 55

The cam 5, revolving in the direction indicated by the dart in Fig. 1, strikes the upper end of the lever 6, thereby pressing its lower end against the rigid arm 9, which extends from the warning-wire 7, and presses said arm 60 to one side, thereby forcing the hook 10 out of the notch in its cam 11 and bringing the hook 12 into position to engage the pin 13, and thereby prevent the wheel upon which said pin is mounted from moving farther until the upper end of the lever 6 drops off the shoulder of the cam, thereby releasing the warning-wire and permitting the strike mechanism to operate in the ordinary manner. 65

All of the parts of the striking mechanism 70 are old excepting the rigid arm 9, which extends upwardly into the clock-case to the lever 6, which lever, in connection with the cam 5, forms a strike-tripping mechanism.

I am aware that in some striking mechanisms the warning-wires, &c., which are usually termed the "lock-work," are arranged to fall into position by gravity, while in other striking mechanisms they are spring-actuated, so as to be operative when the clock is in any 80 position. The lock-work must be spring-actuated when it is set with the plates of the striking mechanism in a horizontal position, as shown in the drawings. 75

A prior patent shows and describes a clock 85 having a cam and drop lever within its case and a bell-striking apparatus outside said case for striking a bell capable of being heard miles distant by the action of a clock of small size. A cord extends from the drop-lever within 90 the clock-case to a drop-lever near the bell-striking mechanism, the latter drop-lever being provided with a spring-pressed toothed pawl, which holds other levers, some of which are spring-pressed and one of which is 95 notched to hold and release an arm that extends from a shaft somewhat analogous to the warning-wire of a clock-striking mechanism. These last-mentioned levers with their springs, notches, and toothed pawl are out- 100

side of the clock-case and are essential parts of the tripping mechanism. The arm which extends to this tripping mechanism does not enter the clock-case or even extend 5 to a point near said clock-case. Such a clock and bell-striking mechanism is hereby disclaimed.

I am also aware that ordinary alarm-clocks have been made with a separately-constructed 10 alarm mechanism set below the time mechanism and connected by a wire or cord, one end of which was attached to an arm that projected from the pallet of the alarm mechanism and the other end attached to a trip-lever 15 on the time mechanism, and that a prior patent shows this ordinary alarm-clock with the time and alarm movement in separate chambers. Such alarm-clocks are hereby disclaimed.

20 I claim as my invention—

1. The herein-described striking-clock, consisting of a clock-case, a time-movement hav-

ing a strike-tripping mechanism within said case, and a striking-movement outside said case having a rigid arm extending from the 25 warning-wire to a point by the side of the tripping mechanism within the clock-case, substantially as described, and for the purpose specified.

2. The combination of a clock-case, a time-movement within said case, the cam 5, attached to and moving with said time-movement, the tripping-lever 6, having one end in engagement with said cam, and the striking mechanism separate from the time-move- 30 ment and having an arm disunited from said lever and extending from the warning-wire to a point by the side of the other end of said lever, substantially as described, and for the purpose specified.

ALMERON M. LANE.
